ELECTRON RAY INDICATING DEVICE

J. Albert Hultquist, Scarsdale, N. Y., assignor to
Radio Corporation of America, a corporation
of Delaware

Original application July 23, 1940, Serial No.
346,918. Divided and this application Decem-
ber 20, 1941, Serial No. 423,705

4 Claims. (Cl. 250—27.5)

This invention relates to electron ray indicator tubes and is a division of my copending application, Serial #346,918, filed July 23, 1940.

In frequency modulation receivers it is extremely important that the receiver be tuned to the exact center of deviation of the transmitted wave in order to avoid distortion and noise. Previously known systems, of which I am aware, for indicating correct tuning of frequency modulation receivers depend on the use of a meter or electron ray tube so connected as to give an indication proportional to the voltage developed on the grid of the limiter stage in the receiver, a very sensitive zero center voltmeter across the output of the discriminator stage, or a dual shadow electron ray tube with one of its associated amplifiers connected to one end of the discriminator output circuit and the other connected as a phase inverter. Correct tuning in the first mentioned system is indicated by a maximum grid potential or a closure of the shadow of the electron ray tube. However, this system is rather insensitive to variations in tuning since the response characteristic of the tuned circuits in the receiver is quite broad. It is, therefore, difficult to adjust the receiver for equal response to equal frequency deviations on each side of the midfrequency. Furthermore, the maximum response at this point in the receiver has no relation to the tuning of the discriminator stage and if any change in tuning takes place there the tuning indicator can no longer be relied upon.

In the last of the above mentioned systems proper tuning is indicated by equal sized shadow areas on both sides of the tube. The comparison of a two shadow area is attended with some difficulty since the broadest parts of the shadows are separated by a considerable distance.

The use of a zero center voltmeter overcomes the foregoing disadvantages but it is expensive and easily damaged.

An object, therefore, of the present invention is to overcome the above mentioned difficulties.

A further object of the present invention is the provision of a simple, inexpensive system for indicating correct tuning of a frequency modulation receiver.

Another object of the present invention is the provision of an electron ray structure for giving an indication of the relative intensities of a pair of potentials in the form of substantially triangular shadow areas with variable length bases, said bases being closely adjacent for ready comparison.

Still a further object is the comparison of the

relative magnitudes of a pair of independent potentials.

The foregoing objects, and others which may hereafter appear, are attained by providing a novel form of electron ray indicator tube having a luminous coating on an anode in the form of a pair of intersecting plane surfaces between a pair of separate emitting cathodes and shadow control electrodes. The line of intersection of the planes is in a plane perpendicular to a line between said cathodes. Electron beams from each of the cathodes impinging on the adjacent surface of the anode cause the luminous material thereon to fluoresce. The control electrodes cast triangular shadows on the anode, the width of the shadow at the apex of the anode being proportional to the voltage applied to the ray control electrodes. Since the widest parts of the shadows are closely adjacent they may be readily compared.

The present invention may also be embodied in a pair of conventional single shadow electron ray tubes with their areas placed as closely adjacent as possible, or a tube of the type disclosed in a prior Roberts Patent #2,175,700, granted October 10, 1939, may be utilized, interposing between the end of the tube and the eye of the observer a pair of reversing prisms so that the widest parts of the shadows appear adjacent to each other.

The present invention will be more fully understood by reference to the following detailed description, which is accompanied by a drawing in which Figure 1 is a circuit diagram illustrating the application of my invention to the discriminator circuit of a frequency modulation receiver; Figure 2 is an end view of an embodiment of the present invention and illustrates the indication given when employed in a circuit as shown in Figure 1; Figure 3 is a view partly in section of the embodiment of Figure 2, while Figure 4 illustrates a modification of the invention.

In Figure 1, 10 indicates generally a discriminator transformer of the frequency modulation receiver. Frequency modulated signals of a constant amplitude are applied to the primary 11. To the secondary 12 of the transformer are connected the anodes of rectifier tube 14. The windings of the transformer are tuned to the desired frequency by means of adjustable condensers 13, 13'. Across the cathodes of rectifier 14 is connected an output circuit comprising resistors 15, 16 shunted by radio frequency bypass condensers 17, 18. One end of the output circuit is grounded and the other end is connected to an audio fre-

quency load circuit, as indicated by lead 20. The junction between resistors 15 and 16 is connected through a radio frequency choke 21 to a center tap on the secondary 12 of discriminator transformer 10. The center tap is also coupled to condenser 22 to the high potential side of primary 11.

The discriminator circuit, described briefly above, does not form a part of the present invention and the theory of its operation will not here be gone into. However, it is important to understand that when the circuit is properly tuned to a signal to be received the potential across resistor 15 is equal in magnitude and opposite in polarity to that across resistor 16. Therefore, no D. C. potential difference exists between lead 20 and ground. On one side of resonance 20 will become positive due to an increase in potential across resistor 15 and a decrease across resistor 16, while on the other side of resonance the reverse condition will be true. The theory of operation of the discriminator circuit is more completely discussed in a Seeley Patent #2,121,103, granted June 21, 1938, and reference may be made to that patent for a further disclosure.

Through a decoupling circuit 25, 26, a grid 27 of an amplifier and phase inverted tube 28 is connected to the upper end of load circuit 15, 16. The time constant of circuit 25, 26 should be high enough that the audio frequency signal is filtered out and does not appear on grid 27. Dual triode amplifier tube 28 may, of course, be replaced by a pair of physically separate triodes, if desired. Anodes 29 and 30 of the amplifier tube 28 are connected to the positive sides of a source of anode potential indicated as B+ through resistors 31 and 32. The other side of the anode potential source is grounded. The cathodes are connected together and to ground through resistor 39.

Indicator tube 33 has ray control electrodes 34 and 35 connected to anodes 29 and 30 respectively. The anode 36 of indicator tube 33 and its cathodes 37, 38 are connected to the anode supply source in the conventional manner. The magnitudes of plate resistors 31, 32 and the common cathode resistor 39 associated with tube 28 are so adjusted that with no potential on grid 27, equal potentials, somewhat lower than the potential on anode or target 36, are impressed on ray control electrodes 34, 35 of indicator tube 33. The shadows cast on the luminous surface of anode 36 are, therefore, of equal size, as shown in Figure 2. When grid 27 has a positive potential applied thereto, the plate current through resistor 31 increases causing control electrode 34 to become more negative thus increasing the width of the shadow cast thereby on luminous surface of anode 36. The increased current flow through resistor 39 causes the grid 27' of the phase inverter tube 28 to become effectively more negative with respect to anode 30, decreasing the anode current through resistor 32. The potential on ray control electrode 35 of indicator tube 33 therefore becomes more positive, decreasing the width of its shadow on the luminous surface of anode 36. The reverse action takes place when grid 27 has a negative potential applied thereto.

It will be noted that a pair of triangular shadows are formed having closely adjacent variable length bases. It will be readily seen that it is very easy to determine by inspection the relative sizes of the bases of the two triangles, perfect resonance being indicated by the shadow edges

cast by the two ray control electrodes 34, 35 being exactly adjacent.

When the receiver is tuned to a frequency remote from any incoming signal the same indication is obtained. As the tuning of the receiver is varied and resonance with a received signal is approached, the length of the base of one of the shaded areas increases and that of the other decreases until a certain ratio, dependent upon the constants of the circuits and the strength of the signal, is attained. Then as resonance is still more closely approached the larger shaded area decreases in size and the smaller one increases until the base lengths are again equal. The receiver is then correctly tuned. Upon a continued variation of the tuning in the same direction, the change in size of the shaded areas is reversed until again the receiver is tuned to a frequency outside the range of any incoming signal and both shadow areas are again equal in size.

Figure 3 shows partly in section a perspective view of a tube constructed according to my invention. The form of the bi-planar anode or target 36 is clearly shown in this figure. Ray control electrodes 34 and 35 and cathodes 37 and 38 are constructed in the same manner as described in the heretofore mentioned Roberts patent. Likewise, shielding caps 40 and 41 are provided over the ends of the cathode and ray control electrodes in order to shield the eye of the observer from the direct light of the cathodes and in order to prevent fluorescence of the glass envelope 42 of the tube. If desired, semi-cylindrical shells supporting caps 40 and 41 may be substituted for supporting rods 43 in order to prevent fluorescence on the sides of the glass envelope 42. Furthermore, in some cases it may be desirable to provide a low wall bisecting the external angle between the planes of anode 36 for this same purpose, and to prevent a "spill-over" of fluorescence at the apex of the anode. The wall, being thin, and in a plane parallel to the line of sight of the observer causes no obstruction to vision. Grids 37' and 38' may surround cathodes 37 and 38 for limiting the space current drawn from the cathodes if desired. The elements within the glass envelope 42 are supported in position by support rods 45 and mica discs 46, as is customary practice in the construction of thermionic discharge tubes.

A modification of the present invention is shown in Figure 4 wherein an electron-ray tube of the type shown in the Roberts Patent #2,175,700 is used in the circuit shown in Figure 5. The tube is indicated generally by reference character 50. In order to cause the broadest parts of the shadow areas to appear adjacent, a pair of reversing prisms 51 and 52 are placed between the end of the tube 50 and the eye of the observer. These prisms may be formed of glass or any of the recently discovered transparent synthetic plastics such as "Lucite." The operation of prisms 51 and 52 is well understood by those skilled in optical art and it is not believed necessary to discuss their operation further than to say that because of their interposition the widest parts of the shadow areas on anode 53 of tube 50 appear to be closely adjacent so that they may be readily compared.

In either of the forms of my invention described above, an instantaneous check of the condition of the indicating system may be had by tuning the receiver away from any signal or by removing the rectifier tube 14. The absence of a diamond-shaped shadow area as shown in Figure

2 indicates that the balance of the indicating circuit has become disturbed through variation of the circuit elements or aging of the tubes. Resistors 31 and 32 must be varied to again arrive at a balance or amplifier tube 28 and/or indicator tube 33 replaced.

I claim:

1. A thermionic discharge tube having an anode in the form of a pair of intersecting planes, said anode having a luminescent material thereon, a pair of cathodes, one adjacent each anode plane, for directing a stream of electrons on different surfaces of said anode whereby said areas become luminous, the line of intersection of the planes of said anode being normal to a line connecting said cathodes, ray control electrodes adapted to cast triangular shadows on the luminous areas of said anode, one ray control electrode being located between each of said cathodes and said anode and operative to control the length of the base of the triangular shadow cast thereby in proportion to potentials applied to said ray control electrode.

2. A thermionic discharge tube having an anode in the form of a pair of intersecting plane surfaces, said anode having a luminescent material thereon, a pair of cathodes adjacent said

anode for directing streams of electrons on different surfaces of said anode whereby said surfaces become luminous, the line of intersection of the planes of said anode being normal to a line connecting said cathodes, ray control electrodes located along said line between said cathodes and adapted to cast triangular shadows having constant heights and bases variable in length in proportion to potentials applied to said ray control electrodes.

3. A thermionic discharge tube having an anode in the form of a pair of intersecting plane surfaces, said anode having a luminescent material thereon, a pair of cathodes one on each side of the intersection of said plane surfaces, an imaginary line connecting said cathodes intersecting said plane surfaces, and ray control electrodes positioned along said imaginary line and located between said cathodes.

4. A thermionic discharge tube having a dihedral anode, said anode having a luminescent surface, a pair of electron sources one on each side of an intersection of the planes of said dihedral anode, and a ray control electrode positioned between each electron source and said anode.
